UNITED STATES PATENT OFFICE.

CLARK E. RANNEY, OF TULSA, OKLAHOMA.

WELL-TUBE-DRAINING DEVICE.

1,312,423.

Specification of Letters Patent.

Patented Aug. 5, 1919.

Application filed November 26, 1918. Serial No. 264,142.

To all whom it may concern:

Be it known that I, CLARK E. RANNEY, a citizen of the United States, residing at Tulsa, in the county of Tulsa and State of Oklahoma, have invented new and useful Improvements in Well-Tube-Draining Devices, of which the following is a specification.

The present invention relates to an improvement in tube draining devices particularly adapted for use with oil well pumps.

In the operation of removing tubing from oil wells it is customary to displace the lower "standing" valve in the working barrel, by lowering the tube and permitting a pin to raise the valve from its seat, for the purpose of permitting oil which is contained within the working barrel to flow back into the well before the tubing is withdrawn.

With the devices heretofore employed, however, it is necessary to allow the tubing to remain in its lowered position for a sufficient length of time to permit all of the oil contained in the barrel to flow out, which causes a loss of power, reduces the production of the well, etc. Further, with the devices heretofore provided for draining such tubing, the fluid will not escape from the working barrel except to the level of the oil in the surrounding pocket or well, and, therefore, a considerable amount of oil is frequently withdrawn with tubing, which is a total loss as well as causing inconvenience to the workmen by escaping from the tubing onto the derrick floor, etc. as the tubing is drawn from the well.

The object of the present invention is to provide a construction by which the standing valve is not only displaced from its seat, by the means heretofore commonly employed, for example, but will be automatically supported in its lifted position so that withdrawal of the tubing from the well may be instantly commenced and all of the oil contained in the working barrel will be permitted to escape, or flow back into the well instead of being withdrawn with the tubing.

50 In the accompanying drawings:

Figure 1 is a vertical sectional view

through a portion of the working barrel of an oil well pump.

Fig. 2 is a detail view, on an enlarged scale, of the standing valve of the pump 55 and a portion of the working valve, removed from the working barrel.

Fig. 3 is a transverse section on line 3—3 of Fig. 2.

Referring to the drawings, 10 designates the body of the working barrel of an oil well pump which, as usual, is provided at its lower end with a perforated anchor section 11, which parts are of ordinary construction. Within the working barrel 10 is arranged the "standing" valve which comprises a suitable casing 8 having formed therein a valve seat 5 with which a ball valve 3 is adapted to coöperate.

4 designates a pin or rod which extends 70 freely through a guide 11^a in the perforated section 11, being supported on said guide by a nut 4^a engaging a suitable thread. This rod 4 is of such length that, as usual, it projects below the lower end 75 of the perforated anchor 11 so that when its lower end is in contact with the bottom of the well the anchor and working barrel may be moved downwardly relative thereto to cause the upper end of such pin to 80 raise the ball 3 from the seat 5, or shift it from the position shown in the dotted lines in Fig. 2 to the full line position shown in that figure.

A plurality of pivotally mounted spring 85 fingers 1 are arranged to extend through slots formed in the casing 8 of the standing valve so that the upper ends 1^a thereof will project slightly over the ball valve 3 when the latter is in position on the seat 90 5. As said valve is pushed upward by the action of the finger 4 when the working barrel is lowered, said fingers will yield to permit the valve to pass but will immediately spring inwardly again so as to 95 support the valve in the lifted position shown in full lines in Fig. 2. When the ball valve 3 is thus supported, oil contained in the working valve can freely pass about said valve and through the lower end 100 of the casing 8 and out into the well through the perforated anchor section 11. As the

- valve 3 is automatically retained in its lifted position as regards its seat 5, the operators may immediately begin the operation of withdrawing the tubing from the well instead of having to wait, as with the devices heretofore employed, a considerable length of time to permit the oil contained in the working barrel between the valves thereof to escape.
- 10 Means are provided whereby the valve 3 will be automatically returned to its operative position on the seat 5 during the first downward movement of the plunger and working valve of the pump.
- 15 As shown, the strainer 6 which is commonly arranged below the working valve, a portion of the casing or body of which is indicated at 12, is provided with a depending pin 2 that extends through an opening
- 20 in the upper end of the casing 8 of the standing valve and is of such length that it will contact with the standing valve ball 3 when the latter is in its elevated position, as the working barrel descends, and exert sufficient pressure thereon to move the restraining fingers 1 laterally and allow said ball to fall upon the seat 5. When the ball 3 is in position on the seat 5, there is sufficient space between it and the lower end of the pin 2,
- 25 at the bottom of the stroke of the pump plunger to afford the necessary vertical movement of the ball 3 in the pumping operation and said ball is only brought into the path of movement of the pin 2 by lowering the working barrel relative to the pin 4, as hereinbefore explained. As shown, the pin 2 is connected with the lower end of the strainer 6 of the working valve by a suitable thread and nut 7.
- 30 The advantages of the present invention have been briefly referred to in the foregoing description and will be readily appreciated. By providing means for automatically engaging the ball of the standing valve when the latter is lifted from its seat and restraining it in such elevated position the operatives may immediately begin withdrawing the tubing from a well, thus expediting the operation and saving time and lessening the expense, and further, all of the oil contained in the working barrel will escape therefrom while the tubing is being withdrawn, regardless of the level of oil in the well. The improvements comprise
- 35 a minimum number of parts and may be readily applied to the working barrels of the pumps commonly in use.

Having thus described my invention, what is claimed is:

- 60 1. The combination with the working barrel of an oil well pump, the standing valve within said barrel and means for raising said valve from its seat when the working barrel is lowered a predetermined dis-

tance from its working position, of means 65 for automatically engaging the standing valve and maintaining it in such elevated position, for the purpose described.

2. The combination with the working barrel of an oil well pump, the standing valve within said barrel and means for raising said valve from its seat when the working barrel is lowered a predetermined distance from its working position, of a plurality of spring fingers forming a part 75 of the cage for the standing valve and adapted to extend beneath it when the valve is raised from its seat as aforesaid.

3. The combination of the working barrel of an oil well pump, a standing valve with- 80 in the barrel comprising a casing provided with a suitable seat and a ball movable within said casing toward and from said seat, a plurality of finger-like members pivotally connected with said valve casing 85 and extending into the interior thereof through slots above the valve seat, and means for automatically moving said valve from its seat to a position where it will be supported by said members when the work- 90 ing barrel is lowered a predetermined dis- tance from its working position.

4. The combination with the working barrel of an oil well pump provided with standing and working valves, and means for 95 raising the standing valve from its seat when the working barrel is lowered a predetermined distance from its working position, of means for automatically engaging the standing valve and maintaining it in such 100 elevated position, and means connected with a member of the working valve for disengaging the standing valve from said engaging means on a downward movement of the working valve.

105 5. The combination of the working barrel of an oil well pump, a standing valve within the barrel comprising a casing provided with a suitable seat and a ball movable within said casing toward and from said seat, means for automatically raising said valve from its seat when the working barrel is lowered a predetermined distance from its working position, means for retaining the standing valve ball in its elevated position, 110 and a pin guided in the upper end of the standing valve casing and adapted to be actuated by a downward movement of the working valve of the pump to release the ball of the standing valve from said retain- 115 ing means.

120 6. The combination of the working barrel of an oil well pump, a standing valve with- 125 in the barrel comprising a casing provided with a suitable seat and a ball movable within said casing toward and from said seat, means for automatically raising said valve from its seat when the working barrel is

lowered a predetermined distance from its working position, means for retaining the standing valve ball in its elevated position, and a pin connected with the strainer of the 5 working valve of the pump and adapted when the working valve approaches the limit of its downward movement in the

barrel to contact with the ball of the standing valve and disengage it from the means that hold it away from its seat.

In testimony whereof I have hereunto set my hand.

CLARK E. RANNEY.
